FOOT EXERCISER MAT

Edward G. Altmeier and Donald C. Andreasson, both of
7364 W. Grand River, Brighton, Mich.

Filed Apr. 27, 1962, Ser. No. 190,662

5 Claims. (Cl. 128—25)

This invention relates to a foot exerciser mat and is particularly designed for persons who wish to relax the muscles in their feet and stimulate the circulation therein.

The device comprises briefly a mat formed of a soft flexible material with configurations on the top surface in such design and of such shape that they can massage the muscles and reflexes in the soles of the feet.

It is an object of the present invention to provide a foot massaging device which can be used by a person standing on the mat or by a person sitting and placing his feet on the mat in the front of his chair. The configuration of the mat is such that the effect of it alters with the position of the foot on the mat, portions being raised from the normal level to accommodate the arch of the foot in varying positions.

Another object of the invention is the provision of a mat of the type described which can be readily cleaned and handled.

Other objects and features of the invention relating to details of construction and operation will be apparent in the following description and claims.

A drawing accompanies the disclosure and the various views thereof may be briefly described as:

FIGURE 1 is a plan view of the mat;

FIGURE 2 is a longitudinal section on line 2—2 of FIGURE 1; and

FIGURE 3 is a transverse section on line 3—3 of FIGURE 1.

Referring to the drawing now in detail, the mat 10 is shown as having an elliptical shape although this shape is not critical to the effectiveness of the mat. The mat comprises a base portion 12 and integral protuberances which are preferably formed of a soft rubber material or its equivalent with a durometer hardness preferably ranging from 40 to 60. The central portion of the mat in a more or less rectangular area 14 is profiled by being raised gradually from each side to a high portion and tapers or blends at the sides into the portion 12. Integrally formed with the mat on the surface 16 are small protuberances or knobs 18 surrounding the outer portions of the mat and larger protuberances 20 on the profiled portion 14. The knobs 18 are preferably about $\frac{3}{8}$ " in diameter at their base and about $\frac{1}{4}$ " in height and with a preferred maximum height of $\frac{3}{8}$ ". The larger knobs 20 are preferably about $\frac{1}{2}$ " in diameter at the base, preferably about $\frac{3}{8}$ " in height with a preferred maximum of about $\frac{1}{2}$ ". The marginal mat thickness relative to the center of the raised central portion has a differential of from $\frac{1}{4}$ to $\frac{1}{2}$ an inch while the overall thickness of the mat may vary depending on the flexibility desired. A total thickness of $\frac{3}{16}$ " to $\frac{1}{4}$ " at the outer borders inside the marginal ridge 32 is recommended.

It will be noted that the knobs 18 and 20 are longitudinally and laterally aligned and also diagonally aligned, the spacing being about 1" between centers throughout most of the area of the mat. While the alignment above described and shown in the drawings is preferred from the point of view of ease of manufacture of the dies and the mat, the spirit of the invention includes concentric rings of the protuberances or even a random arrangement as long as the basic general pattern is maintained as to quantity and height. In the portion at the bottom center of the mat below the area 14, as viewed in FIGURE 1, the number of the smaller protuberances 18 is

2

increased to about double. For example, it will be noted that the protuberances in groups of four, such as 22, 24, 26 and 28 have a protuberance 30 in their midst and the same is true of the other groupings of four in this area. The increase in density of the protuberances at this point is provided to support the heel of the user where the flesh is a little closer to the bone and the weight is of greater concentration. Above the central portion 14 are three of the larger protuberances 40 to contact the big toe area of the foot.

In the use of the mat, a person removes his shoes and either with bare feet or light stockings he faces the mat as it appears in FIGURE 1 and moves on to it preferably with his feet spread apart to avoid the central section 14. The feet can then be moved gradually toward the center of the mat, one at a time, where the increased height due to the larger protuberances and the profiled central portion moves into the arch portion of the foot and exercises the muscles and reflexes of the arch as well as on the bottom of the foot. The result of standing on a mat of this design for a period of even five minutes is a complete stimulation of the muscles and reflexes of the feet; the relaxation thereof has a beneficial effect on the entire body. The mat is preferably formed of a non-porous material which is easily washed and maintained in a sanitary condition. It is also preferably formed of a material which is flexible enough that the mat can be rolled up when not in use.

We claim:

30 1. A mat for relaxing and massaging of the feet comprising:

- (a) a base of flexible material,
- (b) a plurality of upstanding protuberances arranged on said mat, said protuberances being spaced and aligned longitudinally, laterally and diagonally,
- (c) said mat having a thickened central portion raised above the remainder of the mat and blending gradually into the surface of the remainder of the mat, and
- (d) there being provided along one side of the mat between one edge and the raised central portion, double the number of protuberances as elsewhere on the mat, the added protuberances being aligned longitudinally, laterally and diagonally and interspaced with the other protuberances.

35 2. A mat for relaxing and massaging of the feet comprising:

- (a) a base of flexible material,
- (b) a plurality of upstanding protuberances arranged on said mat, said protuberances being spaced and aligned longitudinally, laterally and diagonally,
- (c) said mat having a thickened central portion raised above the remainder of the mat and blending gradually into the surface of the remainder of the mat, and
- (d) the protuberances on the raised portion of the mat being higher than the protuberances on the remainder of the mat, and
- (e) the protuberances along one side of the mat between one edge and the central portion being doubled in number by intermediate spacing relative to each group of four protuberances.

40 3. A mat as defined in claim 2 in which:

- (a) the protuberances are each domed in a rounded shape tapered to the base,
- (b) the base and the protuberances being integral and composed of a soft, resilient material.

45 4. A mat as defined in claim 2 in which:

- (a) the protuberances throughout the mat are between $\frac{1}{4}$ " and $\frac{1}{2}$ " in height and the normal spacing is about 1" center to center on longitudinal and lateral lines,
- (b) the area of closely spaced protuberances having

additional longitudinal and lateral lines of protuberances between the normally spaced protuberances.

5. A mat for relaxing and massaging of the feet comprising:

- (a) a base of flexible material having a uniform thickness and flat upper surface over the major portion of its area,
- (b) a profiled section on said mat raised from its edges in a gradual slope from said upper surface to a high central point in the section, and
- (c) a plurality of relatively closely-spaced, round-topped protuberances on said mat of slightly resilient material, and

(d) an area of the mat along one side being provided with more closely spaced protuberances to form heel support for the user.
